DOG COLLAR CLASP

Charles Mintz, 14—15 162nd St., Whitestone, N.Y.
11357, and Robert Katz, 801 Madison Ave., Lakewood,
N.J. 08701

Filed Dec. 15, 1967, Ser. No. 9,797

Term of patent 14 years

(Cl. D30—25)

FIG. 1

FIG. 2

FIG. 3

FIG. 4

FIG. 5

We claim:

The ornamental design for a dog collar clasp, as shown and described.
